United States Patent Office

Des. 186,128
Patented Sept. 15, 1959

186,128

WALL LAMP

Pasquale U. Franzzone, East Greenwich, R.I.
Application April 1, 1959, Serial No. 55,295

Term of patent 14 years

(Cl. D48—4)

F/G. 1.

F/G. 2

The essential features of my design reside in those portions shown in full lines.

I claim:

The ornamental design for a wall lamp, as shown and described.
